DIRECTIONAL ANTENNA SYSTEM

John J. Root, New York, N. Y.

Application October 22, 1949, Serial No. 123,022

6 Claims. (Cl. 250—33.51)

1

This invention relates to high frequency antennas for use in television and frequency modulation receivers.

In the art of television reception, as presently known, it is almost essential to employ a directive antenna which is further of a size to resonate approximately within the frequency range of reception. When the television receiver is in a so-called "fringe area," a term referring to areas at a substantial distance from the television transmitter, it is generally necessary to employ a more or less, elaborate antenna having elements of adequate size to resonate at the desired frequencies. When the receiver is closer to the television station, the antenna may be correspondingly simplified although it is rare in actual practice that one may be dispensed with entirely.

The need for a simple, small antenna for television receivers located in large cities has been very great. A major reason is that the population of such large cities often inhabit apartment houses where the use of a great number of individual, elaborate antennas is inconvenient, if not impossible. Furthermore, the provision of a smaller, simplified antenna obviously offers considerable manufacturing and installation economies. As a result of the above need, there have been developed antennas which are disposed within the television receiver cabinet but, as far as I am aware, such antennas have been extremely inefficient. In addition, it was often necessary to orient the antenna in order to improve reception, and the physical orienting of the cabinets was then necessary. It will be evident that this may be very impractical since the cabinet may be required to be so turned that the viewing tube is directed away from the spectators.

With the above in mind, I have devised an antenna to be incorporated in a television cabinet which is of pronounced efficiency and provides a usable signal within reasonable distances from the television transmitter. The instant antenna employs crossed dipoles, as will hereinafter appear, the dipoles being bridged by an integral antenna element. In addition, the antenna preferably employs what I refer to as an appendix which may be omni-directional as opposed to the directional elements of the antenna.

Orientation of the antenna is electrically provided. In other words, no physical rotation is necessary but a rotary condenser having elements connected to and corresponding to the dipoles serves to electrically rotate the antenna

2

so that the cabinet itself need not be moved at all. Orientation of the antenna is then accomplished by means of a knob disposed on the cabinet which rotates the condenser rotor and effectively orients the antenna.

The antenna of the instant invention may also be constructed without the appendix above referred to but may utilize instead a matching stub as will be hereinafter made clear.

The invention will be further understood from the following description and drawings in which:

Fig. 1 is a perspective view of a television receiver cabinet equipped with the built-in antenna of the instant invention.

Fig. 2 is a fragmentary view taken substantially along the lines 2—2 of Fig. 1.

Fig. 3 is a fragmentary, plan view of a terminal end of one of the antenna dipoles.

Fig. 4 is a substantially schematic illustration 20 of the antenna installation of Fig. 1.

Fig. 5 illustrates a modification of the antenna dipole support.

The cabinet C illustrates a conventional television receiver cabinet but it will be evident that 25 it may assume many diverse forms. In the form shown, the antenna comprises dipole sections 10 and 11 forming one dipole and dipole sections 12 and 13 forming another dipole. The dipoles are maintained in crossed relationship so that 30 they are perpendicular in relation to each other. For convenience of handling and installation, the dipole sections are fastened as by staples 14 to an insulating board 15. Board 15 may be of cardboard or any of the well-known plastic materials 35 generally used for insulation purposes. Board 15 may be fastened to the cabinet ceiling by means of nails or screws 16.

In the form shown, dipole sections 10 and 13 are bridged by an elongated conductor 17 which 40 may be integral with the dipole sections 10 and 13. It has been found that such bridging or short circuiting increases the impedance match between the antenna and the receiver input and further increases gain at the low frequencies.

45 The dipole sections and bridging conductor 17 may take the form of flat metal strips as illustrated. The terminal ends T of the dipole sections are formed as illustrated in Fig. 3 by means of a slot 18 and hole 19, the slot 18 permitting 50 the terminal end to be bent downwardly as illustrated in Figs. 1 and 2 so as to provide a lug to which soldered connections may be made. The hole 19 serves its usual function of permitting the initial introduction of wires 20 and 21 preparatory to soldering them thereto.

Wires 20 and 21 are connected to both terminal ends of one dipole while wires 22 and 23 are connected to the terminal ends of the other dipole. All four wires are then brought out and connected to a terminal strip 24.

Effective orientation of the crossed dipole antenna is accomplished by means of a rotary, substantially tubular condenser 25 having four outer, arcuate stator plates which are insulated from each other. The form of the condenser may follow that described in my prior application, Serial No. 72,700, filed January 25, 1949, but it may further take the improved form illustrated herein.

Wires 20, 21, 22 and 23 are effectively respectively connected to wires 25^a, 26, 27 and 28 which are in turn connected to the lugs 29, 30, 31 and 32 of the condenser stator plates 33, 34, 35 and 36. Thus, each condenser stator plate represents one dipole section. Condenser 25 may be mounted within the cabinet in any conventional manner, the condenser shaft 37 extending therethrough so that an actuating knob 38 may be employed to operate the condenser, as will be hereinafter described.

To the shaft 37 are connected two rotor plates 39 and 40 having capacitative action with the stator plates. It will be recognized that rotation of the plates 39 and 40 will serve to select input voltages from any particular diametrical position of the stator plates. In this way, rotation of the rotor plates acts as quadrant selection in respect to the dipoles to which the stator plates are connected.

Lugs 41 and 42 are respectively connected to the rotor plates 39 and 40 so that wires 43 and 44 represent the output of the antenna and are correspondingly connected to the input of the television receiver. Terminals 45 and 46 represent such receiver input terminals.

A particular advantage is derived by connecting a metallic conductor 47 to either one of the rotor plates or the terminal represented thereby. Thus, conductor strip 47 is connected to terminal 46 and it is made fast to the backboard 48 of the television receiver as by staples 44. Because of the physical appearance of conductor strip 47, I have referred to it as an appendix. Strip 47 is very useful in increasing the gain of the antenna, particularly for the low frequencies. Referring to Fig. 4, I have further illustrated the provision of a lug 49 which is connected to strip 47. It has been found that further gain is accomplished by clipping the strip 47 to the conventional power line cord of the receiver at any convenient point. Lug 49 is therefore provided to facilitate such clipping. It is believed that capacitative action between strip 47 and the ground wire of the power line cord is responsible for such increased gain.

In Fig. 5, I have illustrated the same essential antenna structure except that the board 15 is replaced by a central insulating member 50, the dipole sections being stapled thereto and thereafter being loose or hanging. With this construction, the dipole sections are merely nailed or stapled directly to the cabinet ceiling.

The operation of the antenna system described will be apparent from the above explanation. Briefly, the directional dipoles accommodate signals received from any direction. The signals are then selected through rotation of the variable condenser so as to effectively orient the antenna in space, although it is physically motionless. The conductor 47 which connects the free end of one of the dipole sections to the free end of an adjacent dipole section appears to exercise an in-

ductive effect so as to compensate for the shortness of the dipoles. Conductor strip 47, which is connected to one of the rotor plates, may be of a length approximately equal to either of the dipoles but such length is not critical.

The use of appendix conductor strip 47 may be supplanted by a conventional matching stub connected between terminals 45 and 46. Such matching stubs are well known and are generally U-shaped. Connections to the receiver input may be made along respective points of the arms of the U, such points being selected pursuant to the impedance of the receiver input to be matched. However, neither the appendix conductor strip 47 nor a matching stub is essential to the operation of the antenna system and may therefore be eliminated in constructing a satisfactory antenna.

Details of construction of condenser 25 are not included nor claimed herein. However, the condenser may follow the form described in my prior application as aforesaid but may preferably take the form of a condenser which is the subject matter of a patent application being filed herewith.

Whereas I have referred to the action of the rotary condenser as effectively rotating the dipoles, the condenser inherently embodies other functions and advantages such as properly phasing the picked-up signals although they may be arriving at the antenna out of phase. In addition, it is believed that the condenser provides a tuning action which increases gain.

What is claimed is:

1. A television antenna system comprising a pair of directional elements disposed so as to be effective in substantially mutually perpendicular directions, variable means for electrically combining the outputs of said directional elements so as to effectively orient the pair of directional elements, the end of one of said directional elements being connected to an adjacent end of the other directional element.

2. A television antenna system comprising a pair of dipoles crossed so as to be effective in substantially mutually perpendicular directions, the terminal ends of said dipoles being adjacent each other, variable condenser means connected to said terminals for effectively rotating said dipoles in space, an outer end of one of said dipoles opposite to a terminal end thereof being connected to an outer end of the other dipole.

3. A television antenna system comprising a pair of dipoles crossed so as to be effective in substantially mutually perpendicular directions, the terminal ends of said dipoles being adjacent each other, variable condenser means connected to said terminals for effectively rotating said dipoles in space, an outer end of one of said dipoles opposite to a terminal end thereof being connected to an outer end of the other dipole and a conductor extending from said variable condenser means and being a length approximately equal to said dipoles.

4. A television antenna system comprising a pair of dipoles crossed so as to be effective in substantially mutually perpendicular directions, a rigid support for maintaining said dipoles in crossed position, the terminal ends of said dipoles being adjacent each other centrally of said support, a condenser including four stator and two rotor plates, said rotor plates being arcuate and jointly forming a circle while being insulated from each other, the terminal ends of each dipole being connected to diametrically opposite stator plates, said rotor plates being adapted to provide

voltages by capacitive effect from said stator plates for connection to the input terminals of a television receiver, and an elongated conductor effectively connected to and extending from one of said rotor plates, said elongated conductor terminating in a free end.

5. A television antenna system comprising a pair of dipoles in the form of electrical conductors and crossed so as to be effective in substantially mutually perpendicular directions, said conductors being flexible, supporting means for maintaining said conductors in said crossed relationship, the terminal ends of said dipole conductors being disposed adjacent each other, an electrical conductor extending linearly and connecting the outer end of one dipole conductor opposite its terminal end to the outer end of the other dipole conductor, and variable condenser means comprising four stationary condenser plates, each of said condenser plates being respectively

10

20

connected to the four terminal ends of the two dipole conductors, said variable condenser means further including a pair of rotor plates for electrically rotating the directional characteristics of said crossed dipole conductors.

6. A television antenna system according to claim 5 and including a conductor electrically connected to one of said rotor plates, said last-named conductor being of a length approximately that of said dipole conductors.
